U.S. Appl. No. 62/888,656, filed Aug. 19, 2019, Kukucka.

Primary Examiner — Cynthia R Underwood

(74) *Attorney, Agent, or Firm* — McAndrews Held & Malloy, Ltd.

(57) **CLAIM**

The ornamental design for a BIT, as shown and described.

DESCRIPTION

FIG. 1 is a top and front perspective view of a BIT showing my new design;

FIG. 2 is a front elevation view thereof;

FIG. 3 is a rear elevation thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom and rear perspective view thereof.

The evenly dashed broken lines in the figures illustrate portions of the BIT that form no part of the claimed design. The dot-dash broken lines in the drawings illustrate a boundary line that forms no part of the claimed design.

1 Claim, 7 Drawing Sheets
